UNITED STATES PATENT OFFICE.

JAMES FAIRHEAD, OF TORONTO, ONTARIO, CANADA, ASSIGNOR TO THE LAKE SIMCOE ICE SUPPLY & COLD STORAGE CO., LIMITED, OF TORONTO, CANADA.

ICE-SCORING MACHINE.

1,384,749.

Specification of Letters Patent. Patented July 19, 1921.

Application filed January 26, 1920. Serial No. 353,978.

To all whom it may concern:

Be it known that I, JAMES FAIRHEAD, a subject of the King of Great Britain, and resident of 172 King St. East, in the city of

5 Toronto, county of York, Province of Ontario, in the Dominion of Canada, have invented certain new and useful Improvements in Ice-Scoring Machines, of which the following is a specification.

10 The invention relates to improvements in ice scoring machines as described in the present specification and shown in the accompanying drawing that forms a part of the same.

15 The invention consists essentially of the novel means employed for scoring a large block of ice to facilitate subsequent breaking up into blocks of smaller dimensions.

20 The objects of the invention are to facilitate the delivery of any required weight of ice, to reduce to a minimum the cost of delivering ice, to assure the purchaser of correct weight and generally to provide an ice scoring machine which will be inexpensive 25 to construct, simple of operation, durable and efficient.

The drawing is a perspective view of the machine, portions of the frame work being broken away to disclose various parts of the 30 operating mechanism.

Referring to the drawing the main frame adapted to support the various parts of the machine preferably consists of four uprights 1, 2, 3, and 4 respectively, supported 35 on the floor 5 of the building and suitably connected at their top ends by cross pieces 6.

7 is a platform leading to one end of the machine and located considerably above the floor 5, said platform being for the purpose 40 of supporting the large blocks of ice as they are being fed to the machine for scoring.

8 are curved guide strips secured to inwardly extending blocks 9 from the uprights 1 and 2 respectively, the purpose of said 45 strips being to guide the blocks of ice into the machine.

10 are blocks secured on the opposing faces of the uprights 1 and 2 and the uprights 3 and 4 respectively and carrying 50 metal brackets 11 provided with shaft bearings therethrough, said blocks being located on a slightly lower plane than the platform 7.

12 are shafts rotatably journaled in the 55 bearings in the brackets 11 and carrying on

their ends pulleys 13 located at the rear of the machine, said pulleys being connected by belts 14 to pulleys 15 mounted on the end of the drive shaft 16 which in turn is suitably connected with the source of power 60 (said source of power not being shown in the drawings as the machine may be operated by any known means).

17 and 18 are circular saws by means of which the ice is scored, there being a like 65 number of said saws rigidly mounted on each of said shafts, the saws from one shaft being oppositely disposed in relation to the saws from the other shaft and spaced to conform to the thickness of ice which is to be 70 left uncut so that as a block of ice is forced downwardly on the saws it will be provided with parallel vertical cuts on opposite sides to facilitate subsequent breaking up into blocks of the required sizes. 75

The shafts 12 and the saws 17 and 18 are so positioned that the uppermost edges of said saws will be on a slightly lower plane than the platform 7 while the saws on each shaft are spaced from one another a distance corresponding to the size of blocks required to be cut from the large block. 80

19 are the end members of the carrier adapted to receive the blocks of ice from the platform 7, said ends being in the form of 85 substantially rectangular frames located at the front and rear respectively of the main frame of the machine, said frames being of sufficient width to slide freely between the shafts 12 and being provided adjacent to 90 their top and bottom ends with collars 20 adapted to loosely encircle guide posts 21 vertically arranged between said shafts 12 at each of the corners of said carrier.

22 is a member of substantially channel 95 shape in cross section and connecting the top ends of the members 19.

23 is a bar connecting the lower ends of the ice carrier.

24 is a comparatively narrow platform or 100 ice supporting member adapted to be supported by the bar 23 and being pivotally secured to said bar by means of a pivot member 25 located slightly to the rear of the longitudinal center of said bar 23, 105 said ice supporting member being of sufficient length to project past each end of the ice carrier and terminating substantially flush with the platform 7 and the delivery chute 26 respectively. The under side of 110

the rearmost end of said ice supporting member 24 is tapered from the point at which said member is pivoted to the bar 24 to the end thereof to permit of tilting said member rearwardly after the saws have passed through the ice and thus cause said ice to slide into the delivery chute 26.

27 are comparatively short brackets suspended from the front and rear members respectively of the auxiliary frame 28 directly above the ice carrier and terminating slightly short of the uppermost limit of movement of the end members 19 of said ice carrier.

10 29 are metal straps or catches hingedly secured to the brackets 27 and projecting downwardly therefrom and having substantially hook shaped ends 29^a adapted to engage the under sides respectively of the top 20 bars of the members 19 for the purpose of supporting the ice carrier in its uppermost position, that is to say with the platform 24 on the same plane as the platform 7.

30 is a rod connecting the catches 29 to 25 permit of simultaneous movement to both of said catches.

31 is a handle secured to the front catch 29 for moving the catches into or out of engagement with the ice carrier.

30 Upon the removal of the ice from the carrier to the delivery chute the said carrier is automatically raised to its uppermost position by means of a counter balancing weight 32 connected to said carrier by sprocket 35 chains 33, of which there are preferably two in number, secured adjacent to opposite ends respectively of said weight and the member 22 and operating over sprocket wheels 34 rigidly mounted on a shaft 35, said shaft 40 being rotatably mounted in bearings in brackets 36 secured to the uprights 1 and 3 of the main frame.

37 is a bar slightly greater in length than the width of the platform or ice supporting 45 member 24, said bar being supported on a horizontal plane adjacent to the floor 5 and between the end of the platform 7 and the adjacent end 19 of the ice carrier by means of cables or rods 38 secured to each end 50 thereof and projecting upwardly through the front member of the auxiliary supporting frame 28.

39 is a hand lever adapted to be loosely supported on a rod 40 secured to the uprights 1 and 2 respectively of the main frame, said handle being provided with outwardly radiating ends 41 adapted to be pivotally connected to the upper ends of the cable or rods 38 so that upon the lowering 60 of the handle end of said lever said rods or cables will be forced upwardly drawing the horizontally disposed bar 37 with them and, when the ice carrier is in its lowermost position after having lowered the ice below the 65 saws, raising the front end of the platform

24 and causing the ice thereon to slide rearwardly on to the chute 26.

42 are braces preferably secured to the blocks 9 and projecting inwardly therefrom and being provided with openings therein 70 adapted to permit of the rods or cables 38 sliding freely therein said braces being to hold said rods or cables to their vertical positions.

43 are brackets projecting inwardly from 75 opposite sides of the main frame and being for the purpose of guiding the block of ice to its proper position on the ice carrier.

44 are brackets located at the rear of the machine to prevent the block of ice from 80 sliding out through the end of the ice carrier.

45 is a plunger secured substantially centrally of the member 22 and projecting upwardly therefrom and operating in an oil 85 containing cylinder 46 which may be suspended from the ceiling of the room or from any desired form of bracket.

In the operation of this invention the ice 90 carrier or elevator, which under normal conditions, that is to say when there is no weight thereon, rests in its uppermost position due to the weight of the balance member 32, is first locked against downward movement by simply pushing on the handle 95 31 which forces the hook ends 29^a of the catches 29 under the top members 19 of said elevator. A block of ice is then deposited on the platform 24 and the catches 29 are released from engagement with the elevator and 100 as the combined weight of said elevator and said block of ice is greater than that of the balance member 32 said elevator will gradually descend and as the block of ice is greater in width than the distance between the opposing saws said ice will be scored vertically 105 on opposite sides by the swiftly revolving saws.

When the ice has passed the saws and it is desired to deposit it on the delivery chute 26 110 it is simply necessary to pull downwardly on the lever handle 39 thus raising the rods 40 thereof and consequently the member 37 and as said member 37 engages the under side of the projecting end of the platform 24 115 said platform is tilted rearwardly causing the ice to slide on said delivery chute by the aid of which it is deposited in any desired location.

Coincidently upon the removal of the ice 120 from the elevator said elevator will be automatically started on its return to its uppermost position by the weight member 32 and upon reaching said position may be again locked by means of the catches 29.

125 As the ice carrier or elevator is reciprocated the plunger 45 is operated within the oil cylinder 46 thus holding said elevator to a true vertical movement and assuring a smooth and even motion so as to eliminate 130

any possibility of the saws becoming damaged, such as might result from any uneven movement of the block of ice.

While I have thus described the preferred 5 construction, combination and arrangement of parts which constitute the present invention, it is obvious that various changes may be made without departing from the spirit and scope of the invention as contained in 10 the claims for novelty following:—

What I claim is:—

1. In an ice scoring machine, a main frame, parallel horizontal shafts rotatably mounted in bearings in said frame and 15 carrying saws rigid therewith, means for rotating said shafts, an elevator reciprocating on a vertical plane between said shafts and adapted through the weight of ice placed thereon to lower said ice between opposing saws for scoring, said elevator being provided with a tilting floor, means for tilting said floor for delivering said ice from 20 said elevator, a weight member adapted upon the removal of said ice from said elevator to return said elevator to its position above said saws, and a lock for said elevator.

2. In an ice scoring machine, a main frame, parallel horizontal shafts rotatably mounted in bearings in said frame and carrying saws rigid therewith, the saws from one shaft being oppositely disposed in relation to those from the other of said shafts, an elevator reciprocating on a vertical plane 35 between said shafts and adapted through the weight of ice placed thereon to lower said ice between opposing saws for scoring, said elevator being provided with a tiltable floor, a balance member connected to said 40 elevator by flexible members operating over pulleys mounted above said elevator, said balance member being adapted upon the removal of ice from said elevator to return said elevator to its uppermost position, 45 means for tilting said floor for delivering the ice from said elevator, and a catch adapted to hold said elevator to its uppermost position.

3. In an ice scoring machine, a main frame 50 comprising uprights and cross pieces, parallel horizontal shafts rotatably mounted in bearings in said frame, means for rotating said shafts, saws rigidly mounted on said shafts at intervals, the saws from one shaft 55 being oppositely disposed in relation to those from the other of said shafts, said opposing saws being spaced a distance corresponding to the thickness of ice to be left uncut, an elevator slidably mounted on vertical rods located between said shafts adjacent to the front and rear respectively of said frame, said elevator comprising top 60 and bottom and end members, the bottom of said elevator being provided with a tiltable platform projecting forwardly therefrom 65

and adapted to receive a block of ice, flexible members secured to said elevators and operating over pulleys and carrying one or more weights adapted to hold said elevator normally to its position above said saws, 70 manually operated means adapted to raise the projecting end of said platform for discharging the ice from said elevator subsequent to scoring, and catches adapted to hold said elevator to its uppermost position. 75

4. In an ice scoring machine, a main frame comprising uprights and cross pieces, parallel horizontal shafts rotatably mounted in bearings located at the front and rear respectively of said frame, means for rotating said shafts, circular saws rigidly mounted on said shafts at intervals, the saws from one shaft being oppositely disposed in relation to those from the other of said shafts, 80 said opposing saws being spaced a distance corresponding to the thickness of ice to be left uncut, rods vertically arranged between said shafts adjacent to the front and rear ends respectively of said frame, an elevator comprising end members slidably supported on said vertical rods and connected by top and bottom pieces, a rearwardly tiltable platform mounted on said bottom pieces and projecting forwardly therefrom and terminating flush with a delivery platform, a balance member holding said tiltable platform normally on a plane with said delivery platform, said balance member and said elevator being connected by flexible members 90 operating over pulleys rotatably mounted on a plane above said elevator, manually operated means for tilting said platform subsequent to said elevator reaching its lowermost position, and a discharge chute receiving the ice from said elevator. 95

5. In an ice scoring machine, a main frame comprising uprights and cross pieces, parallel horizontal shafts rotatably mounted in bearings located at the front and rear respectively of said frame, means for rotating said shafts, circular saws rigidly mounted on said shafts at intervals, the saws from one shaft being oppositely disposed in relation to those from the other of said shafts, 100 said opposing saws being spaced a distance corresponding to the thickness of ice to be left uncut, rods vertically arranged between said shafts adjacent to the front and rear ends respectively of said frame, an elevator comprising end members slidably supported on said vertical rods and connected by top and bottom pieces, a rearwardly tiltable platform mounted on said bottom piece and projecting forwardly therefrom and terminating flush with a delivery platform, a balance member holding said tiltable platform normally on a plane with said delivery platform, said balance member and said elevator being connected by flexible members 105 operating over pulleys rotatably mounted on a plane above said elevator, manually operated means for tilting said platform subsequent to said elevator reaching its lowermost position, and a discharge chute receiving the ice from said elevator. 110

6. In an ice scoring machine, a main frame comprising uprights and cross pieces, parallel horizontal shafts rotatably mounted in bearings located at the front and rear respectively of said frame, means for rotating said shafts, circular saws rigidly mounted on said shafts at intervals, the saws from one shaft being oppositely disposed in relation to those from the other of said shafts, 115 said opposing saws being spaced a distance corresponding to the thickness of ice to be left uncut, rods vertically arranged between said shafts adjacent to the front and rear ends respectively of said frame, an elevator comprising end members slidably supported on said vertical rods and connected by top and bottom pieces, a rearwardly tiltable platform mounted on said bottom piece and projecting forwardly therefrom and terminating flush with a delivery platform, a balance member holding said tiltable platform normally on a plane with said delivery platform, said balance member and said elevator being connected by flexible members 120 operating over pulleys rotatably mounted on a plane above said elevator, manually operated means for tilting said platform subsequent to said elevator reaching its lowermost position, and a discharge chute receiving the ice from said elevator. 125

7. In an ice scoring machine, a main frame comprising uprights and cross pieces, parallel horizontal shafts rotatably mounted in bearings located at the front and rear respectively of said frame, means for rotating said shafts, circular saws rigidly mounted on said shafts at intervals, the saws from one shaft being oppositely disposed in relation to those from the other of said shafts, 130 said opposing saws being spaced a distance corresponding to the thickness of ice to be left uncut, rods vertically arranged between said shafts adjacent to the front and rear ends respectively of said frame, an elevator comprising end members slidably supported on said vertical rods and connected by top and bottom pieces, a rearwardly tiltable platform mounted on said bottom piece and projecting forwardly therefrom and terminating flush with a delivery platform, a balance member holding said tiltable platform normally on a plane with said delivery platform, said balance member and said elevator being connected by flexible members operating over pulleys rotatably mounted on a plane above said elevator, manually operated means for tilting said platform subsequent to said elevator reaching its lowermost position, and a discharge chute receiving the ice from said elevator. 135

erating over pulleys rotatably mounted on a plane above said elevator, a lever having suspension members therefrom carrying a horizontally arranged bar located below the 5 projecting end of said elevator platform and adapted on operation to tilt said platform, a plunger secured to said elevator and projecting upwardly therefrom and operat-

ing in an oil cylinder suspended above said elevator, and ice guiding brackets. 10

Signed at the city of Toronto this 29th day of November, 1919.
